UNITED STATES PATENT OFFICE.

HANNAH JACOBS AND HARRY JACOBS, OF BROOKLYN, NEW YORK.

HAIR DRYING AND WAVING APPARATUS.

1,260,268.

Specification of Letters Patent. Patented Mar. 19, 1918.

Application filed May 10, 1917. Serial No. 167,751.

To all whom it may concern:

Be it known that we, HANNAH JACOBS and HARRY JACOBS, citizens of the United States, and residents of Brooklyn, New York, in 5 the county of Kings and State of New York, have invented certain new and useful Improvements in Hair Drying and Waving Apparatus, of which the following is a specification.

10 Our invention relates to improvements in hair drying and waving apparatus and is in the nature of an improvement over a previous application filed on December 14, 1916, bearing Serial Number 137026 and allowed 15 April 12, 1917.

In a number of establishments more than one set of drying units, comprising one complete apparatus, is used and for such establishments the apparatus disclosed in this application is particularly applicable. It consists essentially of a single unit for supplying air under pressure to all of the sets of apparatus in use in the establishment. We also show a special form of drying unit or 25 tube which may be used in conjunction with this system.

In the drawing Figure 1 is a general view of the apparatus showing piping leading to their terminals and Fig. 2 is a longitudinal 30 section through a drying member particularly adapted to this apparatus.

Referring to the parts, 1 designates a tank or reservoir provided with a pressure gage or indicator 2. The reservoir 1 is kept 35 normally charged with air by means of the compressor pump 3 and motor 4. The capacity of the reservoir 1 is regulated to the requirements at end of the line or main 5 and this capacity is constantly kept up to 40 the requirement by the action of the said pump 3 and motor 4 in conjunction with an automatic control which forms part of the gage or indicator 2, but which is not shown in detail.

45 A blow off valve 6 and a shut off valve 7 are provided in the line 5 near the reservoir and, at predetermined distances or locations, branch mains 8, having shut off and regulating valves 9, may be provided.

50 The said branches 8 terminate in outlets 10 each of which is provided with a valve 11. The said outlets 10 may be grouped in any desired number. On the drawing we have shown but three to a group.

Connected to each outlet 10 by means of 55 a flexible tube 12 is a drying unit 13, shown in enlarged section in Fig. 2 and which consists of an outer tube 14 and an inner tube 15 concentrically connected by means of the head 16. The said head 16 is made of heat 60 resisting material and is formed with a central perforation leading into the tube 15.

The outer tube 14 is formed with the perforations or outlets 18 and is provided with an annular air deflecting rim or ledge 19. 65 The outer tube 14 is further provided with a spirally wound electrical resistance element 20 terminating in the conductor 21 and the said electrical unit 20 is covered with a heat and electrical insulating material 22. 70

Suspending rings 23 may be provided to afford a means for suspending the drying unit when same is in use.

In operation, after the drying unit has been placed over the winding stem with 75 hair upon it, air is allowed to pass through the drying unit 13 where it is heated by means of the electrical resistance unit 20, through which the current has been previously directed. The heated air passing 80 through the heating unit dries the hair upon the stem inclosed within the said drying unit.

The electrical resistance element may be located as indicated by the dotted lines 24 or one electrical resistance unit may be employed for each set or group of outlets. The number of groups or sets of outlets are only limited by the capacity of the reservoir which as hereinbefore stated is constantly charged to the particular capacity required 90 by automatic means.

It is obvious that we may embody various modifications without departing from the spirit of our invention. We do not therefore wish to be understood as limiting ourselves 95 to the particular construction above.

What we claim and desire to secure by Letters Patent, is:

1. In a hair drying and waving apparatus, a hair drying unit adapted to engage 100 and inclose a winding stem having hair wound thereon, a reservoir adapted to contain air under pressure, means for conveying the air from the said reservoir to the said drying unit and means for heating the 105 air in said drying unit.

2. In a hair drying and waving apparatus, a plurality of hair drying units adapted

to engage and inclose winding stems having
hair wound thereon, a reservoir adapted to
contain air under pressure, means for con-
veying the air from the said reservoir to
5 the said drying units and means for heating
the air in the said drying units.

Signed at New York in the county of

Kings and State of New York, this 9th day
of May A. D. 1917.

HANNAH JACOBS.
HARRY JACOBS.
